United States Patent Office

Des. 190,584
Patented June 13, 1961

190,584

DYNAMOELECTRIC MACHINE

Gordon R. Hallenbeck, Amsterdam, Earl K. Stewart, Scotia, and Howard C. Ward, Jr., Schenectady, N.Y., assignors to General Electric Company, a corporation of New York

Filed July 25, 1960, Ser. No. 61,503

Term of patent 14 years

(Cl. D26—5)

FIG. 1

Des. 190,584

PAGE 2

FIG. 2

FIG. 3

FIG. 4

FIGURE 1 is a perspective view of a dynamoelectric machine embodying the new design;

FIGURE 2 is a perspective view of the other side of the dynamoelectric machine shown in the FIGURE 1;

FIGURE 3 is a plan view of the machine shown in FIGURE 1; and

FIGURE 4 is a side view in elevation of the machine shown in FIGURE 1.

We claim:

The ornamental design for a dynamoelectric machine, as shown.
